(57) **CLAIM**

The ornamental design for an inspection chuck, as shown and described.

DESCRIPTION

FIG. 1 is a perspective view of an inspection chuck showing my design;

FIG. 2 is a perspective view from another angle of FIG. 1; FIG. 3 is a front view of FIG. 1;

FIG. 4 is a rear view of FIG. 1;

FIG. 5 is a left view of FIG. 1;

FIG. 6 is a right view of FIG. 1;

FIG. 7 is a top plan view of FIG. 1;

FIG. 8 is a bottom plan view of FIG. 1;

FIG. 9 is a perspective view wherein the sensor is separated from the inspection chuck; and,

FIG. 10 is a perspective view wherein the sensor is received in the inspection chuck.

The broken lines shown in the drawings depict portions of the inspection chuck that form no part of the claimed design.
